DESIGN.

J. E. McMENOMAY.

FIRE PLACE GRATE.

No. 15,589.

Patented Dec. 2, 1884.

UNITED STATES PATENT OFFICE.

JOHN E. McMENOMAY, OF PHILADELPHIA, PENNSYLVANIA, ASSIGNOR TO
GILBERT COMBS, JOHN BAWDEN, AND JOHN H. BAWDEN, ALL OF FREE-
HOLD, NEW JERSEY.

DESIGN FOR A FIRE-PLACE GRATE.

SPECIFICATION forming part of Design No. 15,589, dated December 2, 1884.

Application filed October 6, 1884. Term of patent 7 years.

To all whom it may concern:

Be it known that I, JOHN E. McMENOMAY, a citizen of the United States, and a resident of Philadelphia, Pennsylvania, have invented
5 or produced a new and original Design for a Fire-Place Grate, of which the following is a specification.

My design for a fire-place grate is fully shown in the photographic illustration, the design
10 consisting of the ornamentation of the back and side plates of the structure. The back plate is rectangular, and has a central sunken panel provided with ornamentation, the main features of which are a number of stems with
15 leaves and thistles and raised bead, forming the pattern, as shown. The side panels are

ornamented in a similar way, the ornamentation, however, being modified to suit the different shape of the side piece, which has an ogee front. The structure has the usual 20 grated bottom and barred front.

I claim—

A design for a fire-place grate, said design consisting of the back and side plates, with ornamentation shown and described. 25

In testimony whereof I have signed my name to this specification in the presence of two subscribing witnesses.

JOHN E. McMENOMAY.

Witnesses:

JOHN M. CLAYTON,
HARRY SMITH.
